UNITED STATES PATENT OFFICE.

MICHEL G. KHOURY, OF RIO DE JANEIRO, BRAZIL.

MOLDING AND SWAGING DEVICE.

1,308,758.

Specification of Letters Patent.

Patented July 8, 1919.

Application filed August 10, 1916. Serial No. 114,217.

To all whom it may concern:

Be it known that I, MICHEL G. KHOURY, dentist, a citizen of Brazil, South America, residing at Rio de Janeiro, Brazil, have invented certain new and useful Improvements in Molding and Swaging Devices, of which the following is a specification.

This invention relates to a device which may be used in conjunction with dies, as a swage, and which may also be used to cast dies.

Other objects will be apparent from the following description taken in connection with the accompanying drawings in which:

15 Figure 1 is an elevation, partly in section, of a preferred embodiment of the invention;

Fig. 2 is an elevation of the plunger;

Fig. 3 is a sectional elevation of the upper part of the casing;

20 Fig. 4 is a sectional elevation of the ring surrounding the casing;

Fig. 5 is a sectional elevation of the lower part of the casing;

Fig. 6 is a sectional elevation showing the 25 lower part of the casing ready for use in casting the upper die or mold; Fig. 7 is an elevation of the casing, partly in section, showing the process of casting the upper die;

Fig. 8 is a sectional elevation showing the 30 upper part of the casing ready for use in casting the lower die; Fig. 9 is an elevation, partly in section, of the casing showing the process of casting the lower die; and Fig.

35 Fig. 10 is a sectional elevation showing the entire device during the swaging operation.

In the drawing the swage casing comprises two parts 1 and 3 adapted to fit closely on each other and provided with correspondingly cup-shaped cavities indicated 40 by 1^a and 3^a respectively. Openings 1^e and 3^e are provided in the bottom walls of the cavities 1^a, 3^a respectively. The opening 3^e affords communication through the bottom wall or partition 3^e between the cavity 3^a 45 and a cylindrical recess 3^b limited by an upstanding flange 3^f integral with the upper part 3 of the casing. Surrounding the casing is a ring 2 which fits between peripheral shoulders 1^d and 3^d on the parts 1 and 3 respectively and covers the joint therebetween 50 when these parts are assembled for use.

A substantially cylindrical cover or plunger 4 fits into the recess 3^b and has a peripheral shoulder 4^d adapted to abut against the 55 upper edge of flange 3^f when the bottom face of the plunger rests on the partition 3^e.

The parts 1, 2 and 3 are preferably cylindrical in cross-section and suitable means may be provided to prevent their relative angular displacement. Thus, in the embodiment illustrated in the drawings, the part 1 has an upwardly projecting pin 1^e rigidly connected therewith while the ring 2 and part 3 have hemicylindrical recesses 2^b and 3^b adapted to be engaged by said pin. Obviously other equivalent means can be employed for the same purpose.

The swage casing is herein shown as being supported by a base B having a peripheral flange F, but any other suitable or available 70 support such as a table, a plate or the like, may be used instead of the base B.

In operation, when it is desired to cast the dies for shaping an article of sheet metal such as a dental plate, a mass T of plastic 75 material, for example modeling compound, glazier's putty or the like, is introduced into the casing part 1, and a gypsum cast U of the mouth cavity is placed in the desired position on the plastic mass, as indicated in 80 Fig. 6. The ring 2 and part 3 are then fitted on the part 1 and the upper die may be cast by pouring through opening 3^e (Fig. 7) a metal or alloy having a low melting point, for example tin or an amalgam of tin and 85 antimony or lead and antimony, until the cavity 3^a is entirely filled and the metal that is to form the upper die X reaches the upper surface of the annular partition 3^e. When the metal has set, the parts 1, 2 and 3 are 90 inverted, the parts 1 and 2 are removed and the gypsum cast and its supporting material are withdrawn therefrom. Part 3, then in the position shown in Fig. 8, is ready to receive the ring 2 and part 1 which will serve 95 as a flask for casting the lower die. After having provided the exposed surface of the upper die X with a coating of graphite for preventing freshly poured metal from adhering thereto, the ring 2 is fitted on the 100 part 3 and the part 1 is again placed within the ring 2. The lower die Y is then cast by pouring molten metal through the opening 1^e into the cavity 1^a (Fig. 9) until the surface of the metal reaches the outer edge of 105 the opening 1^e. Thus the lower die is shaped by the upper die, after the latter has been made directly by means of the gypsum cast.

To shape the dental plate a metal sheet Z of suitable size is placed on the lower 110 die, the ring 2 is placed on the shoulder 1^d and the part 3 with the upper die supported

therein is placed on the part 1 (Fig. 10). The plunger 4 is then introduced into the recess 3^b and pressure is exerted thereon, either in a continuous manner or by a succession of blows, until the shoulder 3^d comes into contact with the upper surface of the ring 2. The parts of the swage can then readily be taken apart and the plate having the desired shape is ready for use.

10 It will be obvious that various changes may be made in the construction of the swage hereinbefore described without departing from the spirit of the invention as set forth in the appended claims.

15 I claim:

1. A device of the class described comprising a two-part casing, each part having a cavity, in which the dies may be cast and which are adapted to contain the dies 20 when the device is used as a swage, and an opening in the bottom wall of said cavity, a ring adapted to engage the said casing parts and cover the joint therebetween, and a plunger adapted to engage one of said 25 casing parts to transmit motion thereto and cover the opening therein.

2. A device of the class described comprising a two-part casing, the casing parts having registering cavities, in which the dies may be cast and which are adapted to 30 contain the dies when the device is used as a swage, and openings in the bottom walls of said cavities, one of said casing parts having an upstanding flange on the side 35 of its opening remote from its cavity, a ring adapted to engage the said casing parts and cover the joint therebetween, and a plunger adapted to engage said flange to 40 transmit motion to the casing part and cover the opening adjacent thereto.

3. A device of the class described comprising a two-part casing, the casing parts having registering cavities, in which the dies may be cast and which are adapted to 45 contain the dies when the device is used as a swage, and openings in the bottom walls of said cavities, one of said casing parts having an upstanding flange on the side of its opening remote from its cavity, a peripheral shoulder on each casing part, a ring surrounding the joint between said casing parts and adapted to be clamped between said shoulders, and a plunger adapted to engage said flange to transmit motion to 55 the casing part and cover the opening adjacent thereto.

4. A device of the class described comprising a cup-shaped casing member having an opening in the bottom wall thereof,

a second casing member having a cup-shaped portion adapted to rest on the first-mentioned member, a substantially cylindrical hollow portion and a partition between the two portions, said partition forming the bottom wall of said cup-shaped portion and having an opening connecting the two portions, coöperating dies carried by the first mentioned cup-shaped casing member and by the cup-shaped portion of the second mentioned casing member, peripheral shoulders on said casing members, a ring surrounding the joint between said members and adapted to be clamped between said shoulders, and a plunger adapted to reciprocate in said cylindrical hollow portion and to engage said partition to transmit motion to said casing member.

5. A device of the class described comprising a two-part casing, each part having a cavity in which the dies may be cast and which are adapted to contain the dies when the device is used as a swage and an opening in the bottom wall of said cavity, a ring adapted to engage the said casing parts and cover the joint therebetween, 80 means for preventing a relative angular displacement of said ring and casing parts, and a plunger adapted to engage one of said casing parts to transmit motion thereto and cover the opening therein.

6. A device of the class described comprising a cup-shaped casing member having an opening in the bottom wall thereof, a second casing member having a cup-shaped portion adapted to rest on the first-mentioned member, a substantially cylindrical hollow portion and a partition between the two portions, said partition forming the bottom wall of said cup-shaped portion and having an opening connecting the two portions, coöperating dies carried by the first mentioned cup-shaped casing member and by the cup-shaped portion of the second mentioned casing member, peripheral shoulders on said casing members, a ring surrounding the joint between said members and adapted to be clamped between said shoulders, means for preventing a relative angular displacement of said ring and casing parts, and a plunger adapted to reciprocate in said cylindrical hollow portion, said plunger having a peripheral shoulder adapted to bear against the outer edge of said portion when the bottom face of said plunger rests on said partition.

In testimony whereof I affix my signature

MICHEL G. KHOURY.
